(57) **CLAIM**

The ornamental design for a handheld fan, as shown and described.

DESCRIPTION

FIG. 1 is a perspective view of the handheld fan showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof;

FIG. 9 is a perspective view of the handheld fan in a folded configuration;

FIG. 10 is a perspective view of the handheld fan in another folded configuration; and,

FIG. 11 is a perspective view thereof, showing the handheld fan shown in an environment of use with an unclaimed base. The broken lines depict portions of the handheld fan that form no part of the claimed design. Additional broken lines in FIG. 11 showing a base, illustrate environment and form no part of the claimed design.
